CLAIM

The ornamental design for a shoe, as shown and described.

DESCRIPTION

FIG. 1 is a top, left, and front perspective view of an ornamental design for a shoe;

FIG. 2 is a front elevational view of the shoe of FIG. 1; FIG. 3 is a right side elevational view of the shoe of FIG. 1; and,

FIG. 4 is a left side elevational view of the shoe of FIG. 1. The broken lines are included for the purpose of illustrating portions of the shoe that form no part of the claimed design.
